Primary Examiner — John A Voytek

(74) Attorney, Agent, or Firm — Norton Rose Fulbright
 Canada LLP(57) **CLAIM**

We claim the ornamental design for an aircraft winglet, as shown and described.

DESCRIPTION

FIG. 1 is a perspective view of an aircraft illustrating an aircraft winglet according to our new design in use;

FIG. 2 is a perspective view of the aircraft winglet;

FIG. 3 is a front view thereof;

FIG. 4 is a rear view thereof;

FIG. 5 is a top view thereof;

FIG. 6 is a bottom view thereof;

FIG. 7 is a right side view thereof; and,

FIG. 8 is a left side view thereof.

The broken lines illustrate environmental structure and form no part of the claimed design.

1 Claim, 8 Drawing Sheets(56)
